UNITED STATES PATENT OFFICE.

JOHANNES HINKLEIN, OF FRANKFORT-ON-THE-MAIN, GERMANY.

TYPE-WRITING MACHINE.

No. 895,088.

Specification of Letters Patent.

Patented Aug. 4, 1908.

Application filed March 13, 1908. Serial No. 420,933.

To all whom it may concern:

Be it known that I, JOHANNES HINKLEIN, a subject of the German Emperor, and a resident of Frankfort-on-the-Main, Germany, 5 have invented certain new and useful Improvements in Type-Writing Machines, of which the following is a specification.

My invention relates to improvements in type-writing machines of that class in which a 10 rotatable type carrier is mounted in front of the platen and with its axis of revolution in the direction of the vertical central plane of the machine, which carrier supports the type bars arranged in one or more concentric 15 circles about its axis of revolution and adapted to be positioned in front of the platen according to the key struck and to be thrown against the platen by means of a hammer actuated by the said key. And the 20 object of the improvements is to provide an improved carrier for the type bars, in which the said bars have a reliable guide, which is simple in construction and has a comparatively small weight, whereby the cost of 25 manufacture is decreased. And for this purpose the carrier comprises two disks mounted at a certain distance from each other on the axis of the carrier and providing guides for the type bars. The carrier, or its axis, is 30 mounted in two vertically reciprocating slide bars connected to one of the ends of a rock shaft operated by the shift key, whereby a simple construction of this part of the machine is obtained.

For the purpose of explaining the invention, I have shown an example embodying the same in the accompanying drawings, in which the same numerals of references have 35 been used to indicate corresponding parts.

In the said drawings—Figure 1, is a plan of the machine, Fig. 2, is a side view of a portion of the machine, including the platen; Fig. 2^a is a similar view showing the other side of the machine; Fig. 3, is a front view 40 of the type carrier; Fig. 4, is a vertical cross-section through the type carrier supporting means and its actuating mechanism, the section being taken on the line A—A of Fig. 1; Fig. 5, is a cross-section taken on the line 45 B—B of Fig. 4, and Fig. 6, is a front view of the type carrier and its actuating means seen in the direction of the arrow shown in Fig. 4.

In the example illustrated in the drawings, the machine comprises a base plate 1, a paper 50 carriage 2 having a cross-wise movement on

the latter, mechanism 4 for adjusting the type carrier and for throwing the types against a platen 7, and the shifting means 6 for the type carrier 3. The platen is mounted in the usual way in two brackets 8 mounted 60 on the carriage 2. The type carrier comprises two disks 10 11 secured to a rotary shaft 9 and provided with concentric notches affording suitable guides for the type bars 12 carrying types corresponding to the figures 65 to be printed by the machine. The type carrier shaft 9 is mounted in a pair of slide bars 13 14 having a vertical reciprocating movement in brackets 15 16 rigidly secured to the base 1, as shown in Figs. 4, 5 and 6. 70 By rotating the type carrier 3, the types are positioned in front of the platen. The said rotation is effected by a lever 4 having a segmental tooth rack 17 at its front end, which rack is engaged by a pinion 19 rotatably 75 mounted on a bracket 18 and meshing with a spur gear 20 keyed to the shaft 9. By laterally rocking the lever 4, and adjusting the same over a segment 21 showing, on its surface, the letters and figures to be printed by 80 the machine, the type carrier 3 is rotated in such a way as to position the proper type in front of the platen.

For printing a letter or other character, the lever 4 is pushed downwards at the proper position on the segment 21, whereby the forward end of a lever 5 is moved downwards, and as the rear end of said lever 5 is connected with the hammer 22 the latter is moved towards the type carrier 3. Thereby, 85 the face 23 of the hammer strikes against the type located in its path, so as to throw the same, against the tension of a retracting spring 24, against the platen 7. For each of the type bars a spring 24 coiled around the bars 12 and located between the disks 10 90 11 is provided. Their function is to take up part of the momentum of the hammer 22 and to retract the bars into their positions of rest.

The type carrier 3 carries types for printing capital letters, small letters, numbers and other marks required in writing. To dispose all of said characters on the type carrier, the types are arranged in two concentric circles. Therefore, the carrier 3 must be vertically adjusted relatively to the platen according to the type to be printed. For this purpose, the shifting mechanism 6 105 is provided. At its end located below the 110

carrier 3, the shifting rock shaft is so connected with the slide bars 13 14 supporting the latter, that by pushing the shift key 25 downwards and thereby rocking the shaft 6, the carrier 3 is raised upwards, so as to position another set of the type bars in front of the platen. When releasing the key 25, the carrier moves by gravitation back into its normal position.

10 Between the carrier 3 and the platen 7 a type inking mechanism is provided. The latter consists of an inking roller 26 having a link connection with a carrier 27. Normally, the said roller is in the position shown 15 in Fig 2. If a letter is to be printed, the proper type is first moved in contact with the roller 26 by depressing the corresponding lever 4, whereupon the roller 26 or its carrier 27, is raised by further depressing the said 20 lever. Thereby, the type is inked, and the roller is simultaneously moved out of the path of the type, so as to allow the latter to pass through a notch provided in the carrier. To keep the roller in close contact with 25 the type when moving the same upwards, a spring is provided, whereby the roller is pressed against the type.

To provide a reliable guide for the type in front of the platen, a notched plate 28 is 30 provided in front of the latter.

I claim:

1. In a type writing machine, the combination with the platen, a type carrier rotatably mounted in front of the platen with its 35 axis of revolution extending horizontally at right angles to the length of the platen, and comprising a pair of disks mounted on the shaft of the carrier and disposed at a suitable distance from each other, a pair of vertically reciprocating bars supporting the said carrier, a plurality of concentrically arranged sets of type bars movably supported on said disks, a rock shaft, a shift key operatively connected with said rock shaft, a pair of 40 crank arms on said rock shaft engaging said 45 vertically reciprocating arms, means to position said type bars in front of the platen by

rotating the carrier, and means to throw the positioned type bar against the platen.

2. In a typewriting machine, the combination with a cylindrical platen, of a type carrier mounted to rotate about a horizontal axis extending at right angles to the axis of the platen, a series of type supported by the carrier and arranged in a plurality of circular rows extending continuously around the axis of the carrier, a vertically movable support for the type carrier, a rock shaft mounted below the carrier and engaging said type carrier support, a key connected with said rock shaft, a hammer, means for rotating the type carrier to adjust a selected type in the operative row into position to be operated by the hammer, and a lever for rotating the type carrier and actuating the hammer. 65

3. In a typewriting machine, the combination with a cylindrical platen, of a type carrier mounted to rotate about a horizontal axis extending at right angles to the axis of the platen, a series of type supported by the 70 carrier and arranged in a plurality of circular rows extending continuously around the axis of the carrier, means for effecting a relative adjustment between the type carrier and the platen to bring the desired one of said rows 75 of type into operative position, a hammer, a lever mounted to move about both vertical and horizontal axes, a sector carried by said lever, a pinion connected with the type carrier, and an elongated pinion connecting said 80 type carrier pinion and sector, whereby when the lever is rocked about its vertical axis the type carrier will be rotated to adjust a selected type into position to be actuated by the hammer, and means for releasing the hammer controlled by moving the lever about its 85 horizontal axis.

In testimony whereof I have signed my name to this specification in the presence of two subscribing witnesses.

JOHANNES HINKLEIN.
